CLAIM

The ornamental design for a container lid, as shown and described.

DESCRIPTION

FIG. 1 is a front, right and top perspective view of a container lid showing my new design in a closed position; FIG. 2 is a rear, right and top perspective view thereof; FIG. 3 is a front elevational view thereof;

FIG. 4 is a rear elevational view thereof;

FIG. 5 is a right side elevational view thereof, the left side being a mirror image;

FIG. 6 is a top plan view thereof;

FIG. 7 is a bottom plan view thereof;

FIG. 8 is a right side elevational view of a container lid showing my new design in an open position, the left side being a mirror image;

FIG. 9 is a front, right and top perspective view thereof;

FIG. 10 is a rear, right and top perspective view thereof;

FIG. 11 is a front, left and top perspective view thereof; and, FIG. 12 is a front, right, and top perspective view of the container lid of FIG. 1 shown in a position of use on an unclaimed water bottle drawn in broken lines.

The broken lines in FIG. 12 illustrating a water bottle depict environment and form no part of the claimed design. All other broken lines depict portions of the container lid that form no part of the claimed design.
